BATTERY CAP

Leon Q. Harrison, 30758 Fairfax, Southfield, Mich.

Filed July 11, 1963, Ser. No. 75,782

Term of patent 14 years

(Cl. D26—6)

Fig. 1

Fig. 3

Fig. 2

FIGURE 1 is a side elevational view of a battery cap, showing my new design, the cap having substantially the same appearance from all sides;

FIGURE 2 is a bottom plan view; and

FIGURE 3 is a side elevational view, partly in cross section taken along line 3—3 in FIGURE 2.

I claim:

The ornamental design for a battery cap, substantially as shown and described.
